[57] CLAIM

The ornamental design for a vented motorcycle wind screen, as shown and described.

DESCRIPTION

FIG. 1 is a left side elevational view of a vented motorcycle wind screen embodying my new design in position of use, it being understood that the broken lines are for illustration purposes only;

FIG. 2 is a front elevational view taken along viewing plane line 2—2 of FIG. 1;

FIG. 3 is a rear elevational view taken along viewing plane line 3—3 thereof;

FIG. 4 is a top plan view taken along viewing plane line 4—4 thereof; and

FIG. 5 is a bottom plan view taken along viewing plane line 5—5 thereof.

Fig. 3**Fig. 5**
